(57) **CLAIM**

The ornamental design for a portable frame as shown and described.

DESCRIPTION

FIG. 1 is a perspective view of a portable frame.

FIG. 2 is a front view of the portable frame of FIG. 1.

FIG. 3 is a rear side view of the portable frame of FIG. 1.

FIG. 4 is a right side view of the portable frame of FIG. 1.

FIG. 5 is a left side view of the portable frame of FIG. 1.

FIG. 6 is a top view of the portable frame of FIG. 1; and,

FIG. 7 is a bottom view of the portable frame of FIG. 1.

The broken lines showing connection joints are for purposes of illustration and form no part of the claimed design.

1 Claim, 4 Drawing Sheets
